US0D1083664S

(12) **United States Design Patent** (10) **Patent No.:** **US D1,083,664 S**
(45) **Date of Patent:** **** Jul. 15, 2025**

(54) **HYDROPONIC PLANTER**

(71) Applicant: **Changde Xu**, Hubei (CN)

(72) Inventor: **Changde Xu**, Hubei (CN)

(**) Term: **15 Years**

(21) Appl. No.: **29/983,477**

(22) Filed: **Jan. 10, 2025**

(51) **LOC (15) Cl.** **11-02**

(52) **U.S. Cl.**

USPC **D11/144**; D11/155; D26/55

(58) **Field of Classification Search**

USPC D8/1; D11/143, 144, 145, 146, 147, 148, D11/152, 153, 154, 155, 156; D6/403, D6/405, 556, 558, 675.1, 675.3, 680; D26/55

CPC . A47G 7/00; A47G 7/02; A47G 7/044; A47G 7/047; A47G 7/06; A47G 7/08; A47G 7/041; A01G 9/02; A01G 9/021; A01G 9/022; A01G 9/023; A01G 9/029; A01G 27/0002; A01G 27/06; A01G 31/00; A01G 31/02; A01G 31/023; A01G 31/024; A01G 31/025; A01G 31/06; A01G 31/065

(57) **CLAIM**

The ornamental design for a hydroponic planter as shown and described.

DESCRIPTION

FIG. 1 is a perspective view of a first embodiment of a hydroponic planter showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a second embodiment of a hydroponic planter showing my new design;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dash-dash broken lines in the drawings depict portions of the hydroponic planter that form no part of the claimed design.

1 Claim, 16 Drawing Sheets
